Specification of Letters Patent. Patented June 23, 1914.

Application filed October 21, 1911. Serial No. 655,832.

To all whom it may concern:

Be it known that I, JAMES POWERS, a citizen of the United States, residing in New York city, in the county of New York and State of New York, have invented certain new and useful Improvements in Perforating-Machines, of which the following is a specification.

My present invention pertains to an improvement in perforating machines and a portion of the mechanism embodied in this improvement is similar to that shown in United States patents issued to me, Nos. 992,245 and 992,246, but more especially relates to the latter patent.

The said Patent 992,246 covers a type of machine for perforating data cards wherein the field or zone of certain information is irregularly distributed upon the card, this peculiar arrangement necessitating an operative key-lever arranged for each of the settable punches outside of the punches known as the gang punches, the said gang punches having a settable plate and not being operable by individual key levers.

The above noted form of machine is particularly adapted to the type of card known as the census card, and my present improvement upon the punch setting mechanism

adapts the said machine to another type of card which is known as the commercial or business card. In the commercial card the perforations for data are arranged in vertical or longitudinal rows; a sufficient number of these rows being laid out upon a card to answer the requirements of business establishments, one or more rows being included in a vertical or longitudinal zone to suit the circumstances. Due to this vertical or longitudinal arrangement of the rows of data-points, it is only necessary to perforate one hole in each row on the said card, consequently if there are ten data-points in one row it is only necessary to utilize one of these ten at any one time and consequently there is no necessity for each punch in that row having an individual operating or setting key-lever.

For adapting the perforating mechanism of the patented machine before mentioned to the present commercial card and for the further purpose of reducing the cost of construction and manufacture and doing away with the multiplicity of key levers, I have devised a new punch setting mechanism

that is simple and is operable with a single lever to select and set a single punch for perforating any one hole in a single row of data-points.

It will readily be seen in the accompanying drawings that this method of operating to set the punches greatly reduces the number of operative parts in the keyboard, and increases the efficiency of the operator.

A further advantage in my machine is that should it become necessary to utilize a series of punches in conjunction with the columns continuously, throughout a single run of cards in a manner similar to that described in the gang punching mechanism in the previously noted patent, certain of these levers may be set and left locked, the other punches utilized for the variable data being selected and set by hand and being automatically returned after punching the proper hole.

A further advantage in this improved construction in the punch setting levers is that I retain the advantage shown in the Patent No. 992,246 of being able to reset any improperly set punch-setting lever prior to operating the thumb key which sets the perforating and feed mechanism in motion.

In the accompanying drawings Figure 1 is a front elevation with my improved keyboard attached. Fig. 2 is a sectional view taken on line 1—1, Fig. 1, looking in the direction of the arrow. Fig. 3 is a side elevation of the machine. Fig. 4 is a sectional view of the machine taken on the line 3—3, Fig. 3, looking in the direction of the arrow. Fig. 5 is a front view of the cam lever. Fig. 6 is a side view of the same. Fig. 7 is a perspective view of a fragment of the key-retractor bars. Fig. 8 is a perspective view of one of the side supporting members for the said retractor.

A brief description of the coöperating parts of the mechanism, shown therein, will be necessary so as to bring out the advantages of the new method of lever control and punch selector. While the punching mechanism is practically the same as has been disclosed and covered by my previously noted patents, some slight modifications are made therein.

In Fig. 2 is shown a sectional view of the machine taken on the line 1—1, Fig. 1 and shows in substance a card magazine having

cards therein and a card feeding slide 2 having thereon a picker blade 3, the said card feeding slide being connected by a pivot 6 to a lever 5, the opposite end of which is pivoted at 7 to a rearwardly extending frame 8. The lever 5 is in turn pivoted to a lever 9 which in turn is pivoted to a slotted cam link 10, the other end of which is pivoted to the base 11 of the machine at 12.

When the slotted cam link 10 is caused to oscillate by means of a disk cam 13 having thereon a pin 14, the link 10 is caused to oscillate to-and-fro, operating the card feeding slide 2 which is mounted on the sliding gib 4 and is thereby caused to feed one card at a time through the front portion 15 of the hopper and it is there grasped by the actuated feeding rolls 16 and 17 and is fed forward until it comes into contact with the second set of feed rolls 18 and 19, and from thence it passes between the two punch plates 20 and 21. After entering the said punch plates which are beveled at their point of entrance for the purpose of permitting easy access of the card, the card is again seized by a pair of actuated feed rolls 22 and 23, and is fed farther forward until it becomes engaged in a second set of like rolls 24 and 25. The card is thereupon caused to be stopped by means of a pin stop member 26 which pierces the lifting die frame 27, the die bolster 28 and the die plate 21, projecting a short distance into the passage formed between the plates 20 and 21 to intercept the cards, thereby causing the same to come to rest. One of the setting levers, such as 29, is then pulled down to the desired notch 30, the oscillation of this lever moving its sector gear 31 mounted on the shaft 32, thereby causing the selector slide 33, which is rack geared and in mesh with said sector 31, to move forward the required amount. The selector slide 33 is shown as a thin slotted member having teeth 34 on its upper portion, the slot 35 forming the middle thereof, being made to fit a central supporting slide member 36 which is arranged directly over the punches approximately near the center of the machine, and on its bottom side has a downwardly depending lug 37. When this slide member is moved by the sector the lug is carried over the punches, generally denoted by 39, the punch selected being determined upon by the number of notches 30 the selecting or setting lever has been moved in the curved front plate 40.

As indicated in the drawings the lug 37 on one of the slides has been moved so as to remain over the fifth punch from the front of the machine and presuming that this punch was the only one to be utilized and the card already had been placed within the machine as previously described, the machine is set in motion by pushing the thumb-

bar 29' downward, and the punch lifting frame 27 is thereupon caused to move upward by means of a pushing cam 41 having a cam roll 42 at its opposite end, said cam roll 42 being in contact with the cam 43 which is attached to and rotates with the main shaft 44. The push cam 41 moves in the direction of the arrow 45, thereby causing the roll 46 which is attached to the punch lifting frame 27 to come in contact with the curved face 47 of the push cam 41, and causing it to rise as before mentioned. The starting mechanism controlled by bar 29' is the same as described in the previously mentioned patents and as it forms no part of the present application, it need not be described. The card which was previously placed in the machine would then be forced upward toward the loosely suspended punches, the same being hung by their heads in a supporting member 48. Thereupon the punches not having a selector lug 37 opposing them would rise immediately, their weight not being enough to perforate the card, whereas the punch which meets with the obstruction formed by the said lug 37 would be caused to perforate the card, thereupon punch lifting frame 27 is caused, by the contour of the actuating push cam 47, to recede to its normal position, the card stop or registry member 26 is also then withdrawn and the card is fed by the group of feed wheels 22, 23, 24, and 25 into the outer front feed wheels 49 and 50. Immediately in front of the said feeding rolls is placed a receiving hopper or magazine, generally denoted by 51, which is attached by suitable means to the front of the machine and into this hopper 51 the cards are delivered there to be removed at convenience or when said hopper is filled.

The curved plates 40 which are mounted upon the top frame 40' serve as a cover for the front of the mechanism and also as a means for guiding the levers 29 in their swinging movements and as a locking support for the same, each of said levers having its individual slot in which to operate. Each of these guiding slots have located on one side thereof a plurality of short stopping notches 30, there being as many notches in each of these guiding slots as there are punches in the holder 48 which the lever 29 serves, so that when the lever 29 is operated and engages the stop slot at any point, the corresponding punch thereto is in selection and in condition to punch its corresponding hole. For engaging the said notches in said slots, the levers are shown as having short engaging springs 52 thereon which tend to force the lever sidewise and hold the same into the said notches. A slight push with the finger in the case of a wrongly set lever, or one stopped in a wrong notch, causes the release of the said lever and

it can then be reset to the proper notch. After a card has been perforated and fed into the hopper 51, another card has already reached the perforating position, and the setting levers 29 having been automatically reset the machine is then in a position for another perforating operation.

For the purpose of retaining any one of the levers 29 in any desired position, the front upper end of the selector slides have arranged thereon a plurality of notches 53, the number of which corresponds to the number of punches in the row. A bent lever 54 which is pivoted at 55 is held under a downward tension by a spring 56 which is attached to the frame at a point 57. A finger piece 58 is pivotally arranged in proximity to the back end of the lever 54 and is adapted to be oscillated to and fro, as indicated 20 at the dotted position 59, being mounted upon a rod 60. When the finger lever 58 is moved backward to the position 59 the bent lever 54 is released and drops to the dotted position 61, thereby permitting the point 25 to engage in one of the notches 53. As long as the lever 54 remains in the said notch the lever 29 is retained in its set position through the said key levers toothed connection with the said selector slide. When, 30 however, it is desired to release the setting lever 29, the lever 58 is pushed up to the position shown in Fig. 2, this action causing the lever 54 to be raised, thereby withdrawing its point from the notch 53 and permitting 35 the lever 29 to be returned to its normal position by means of the spring 62 which is attached to the lever and to a point 63 at the rear end of the frame.

Each of the levers 29 in the present machine have the combination of the returning spring 62 and the locking levers 58 and 54. For the purpose of absorbing the shock of the return of lever 29 to its normal position through the action of the spring 62, I 45 have arranged at the front end of the machine a pad 64 which may be of soft resilient material, such as felt or the like, which is mounted upon a metal plate 65, which, in turn rests upon springs 66 and 67, so that 50 when the said lever is returned the selector slide 33 is caused to strike the buffer pad 64 and is thereupon noiselessly stopped.

For the purpose of causing the return of the levers 29 which are used for variable 55 data, a plurality of curved bars 68 are mounted by means of screws 69 upon a pair of rods 70 and 71, the said bars having a plurality of notches 72 and 73 therein for the purpose of maintaining the said curved 60 bars 68 properly spaced apart. The rods 70 are so mounted in the machine, Fig. 2, as to lie in close proximity to the curved cover plate 40 and, as indicated in Fig. 4, one of each of the said bars 68 lie between 65 each row of the setting levers 29 and in

such a manner that when the cam 74 is rotated, the raised portion 75 mounted on the inside of said cam, comes in contact with the roll 76 mounted upon the oscillating lever 77, the said lever being pivoted to the main frame at 78 and being in engagement with the two connecting rods 79 and 80. The entire framework formed by the curved bar 68, the rods 70 and 71, and a supporting side frame 81 are thereby caused to move 75 in the direction of the arrow 82', Fig. 1, the said curved bars 68 then coming in engagement with the levers 29, forcing them out of their notches, whereupon the levers are returned to their normal position by the action 80 of the spring 62.

By referring to the sectional view in Fig. 4, one of the side arms 81 is shown at the right hand side of the machine and its opposite supporting member 82 is shown at the 85 left hand side of the machine, and the central shaft 32, upon which both of the said members are slidably mounted, is shown as being fixedly mounted in the main frame. The rods 70 and 71 are shown as being 90 mounted in bosses 83, 84, 85, and 86, which are located in the upper and lower corners of the curved side plate 90 and in which the said rods 70 and 71 reciprocate. A spring 87 is located against a cross frame 95 88, which is mounted in the interior of the setting lever housing, in such a manner as to return the entire key retractor mechanism to its normal position after the roll 76 has passed over the raised portion 75 of the 100 cam 74, thereby leaving the setting lever mechanism ready for the next setting.

By referring to Fig. 5 it will be noted that the upper end of lever 77 is forked and is so arranged as to receive therein the rods 105 79 and 80, the central portion 89 being so arranged as to clear the shaft 32 which passes therebetween.

In Fig. 8 the retractor side frame member 81 has a bore 90 which is adapted to slidably receive the shaft 32, thereby permitting the said side member 81 and its mate 110 82, which is similarly constructed, to move upon the shaft 32 during the retraction of the said setting levers.

Having thus described my invention, I claim:

1. In a card perforating machine of the class described, a plurality of rows of punches, a plurality of punch selectors, a plurality of pivoted setting levers in operable connection with said selectors, and a plurality of latches, one for each of said setting levers whereby any of the said selectors may be maintained in their set positions 120 against return to the normal position until said latches are released.

2. In a perforating machine of the class described, comprised of a plurality of rows of suspended punches, a selector supporting 125

4. In a perforating machine, a set of levers mounted to swing separately, a segment gear carried by each lever, a set of rack bars meshing with the segments respectively to be reciprocated upon oscillation of the levers, a lug carried by each rack bar, a card-punching device including a number of sets of punches, one set for each bar and positioned to be engaged by the lug thereof according to the position in which the rack bar has been set by its operating lever, and means for advancing the punch device to cause engagement of the positioned lugs with one of the punches to effect the perforation of a card in the device. 45
5. In a perforating machine of the class described, comprised of the combination of a plurality of rows of punches, a plurality of slidable punch selectors, a setting lever in operable connection with each of the same and arranged to set said selectors to operate to select and set a punch in one of said rows, means for maintaining said selectors and their operative control in said set positions, means for returning the said selective means to their normal inoperative positions after the selected and set punches have perforated the card, and a buffer arranged in the plane of the said sliding selectors to abut the same as and for the purpose set forth. 50
6. In a perforating machine, a set of levers mounted to swing separately, a segment gear carried by each lever, a set of rack bars meshing with the segments respectively to be reciprocated upon oscillation of the levers, a lug carried by each rack bar, a card-punching device including a number of sets of punches, one set for each bar and positioned to be engaged by the lug thereof according to the position in which the rack bar has been set by its operating lever, means for returning the rack bars and levers after the operation of the punch device, and a latch bar for each rack bar arranged to maintain the rack bar in any of its set positions against the return to normal position by said means. 55
7. In a perforating machine, a set of levers mounted to swing separately, a segment gear carried by each lever, a set of rack bars meshing with the segments respectively to be reciprocated upon oscillation of the levers, a lug carried by each rack bar, a card-punching device including a number of sets of punches, one set for each bar and positioned to be engaged by the lug thereof according to the position in which the rack bar has been set by its operating lever. 60
